UNITED STATES PATENT OFFICE.

EVERETT W. WOLLAM, OF NEW YORK, N. Y.

PICTURE-LIFTER.

No. 909,729.

Specification of Letters Patent.

Patented Jan. 12, 1900.

Application filed January 25, 1908. Serial No. 412,698.

To all whom it may concern:

Be it known that I, EVERETT W. WOLLAM, a citizen of the United States, residing at New York, in the county of New York and State of New York, have invented certain new and useful Improvements in Picture-Lifters, of which the following is a specification, reference being had to the accompanying drawings.

10 My invention relates to improvements in lifting devices for hanging up and taking down picture frames and for other purposes.

The object of the invention is to provide a device of this character which will be 15 simple and inexpensive in construction and which may be conveniently and effectively used for a variety of purposes.

With the above and other objects in view, the invention consists of the novel features 20 of construction and the combination and arrangement of parts hereinafter described and claimed, and illustrated in the accompanying drawings, in which—

Figure 1 is a perspective view of my improved lifting device; Fig. 2 is a vertical section through the same; Fig. 3 is a view similar to Fig. 1 of a modified form of the invention; and Fig. 4 is a top plan view of the device shown in Fig. 3.

30 The invention comprises a pole or hand rod 1 of suitable length and a lifting and supporting head 2 which is mounted on the upper end of the pole or rod and may be constructed of malleable sheet iron or other 35 metal, as shown in Figs. 1 and 2, or of heavy wire, as shown in Figs. 3 and 4. When the head is constructed of sheet metal it is formed from a single piece of substantially rectangular shape by forming at one of its 40 ends two parallel longitudinal slits which provide two spaced arms 3, 4 and an intermediate portion 5 which is bent downwardly to an angular position and then curved transversely to provide a semi-cylindrical 45 attaching shank. The latter is adapted to fit approximately half way around the pole 1 and, owing to its angular disposition, causes the flat body portion of the head 2 to be disposed in an inclined or angular position, as 50 clearly shown in Fig. 2 of the drawings. The attaching shank or portion 5 is preferably set in the pole 1 and secured thereto by transverse pins, rivets or the like 6.

To cause the body portion of the head 2 55 to be more firmly supported in its angular position and to be more securely attached to

the pole, I bevel the upper end of the latter, as shown at 7, so that it bears against the bottom face of the center of the head, and I provide an aperture in the latter to receive 60 a nail, screw or similar fastening 8 which passes into said beveled end of the pole, as shown in Fig. 2. The lower extremities of the spaced arms 3, 4 are bent upwardly to provide hooks 9 adapted to engage a picture 65 frame supporting wire, as presently explained.

In the upper end of the head 2 is formed, upon one side, a transverse notch or recess 10 which extends almost the full width of 70 said head and which provides a laterally projecting and horizontally disposed tongue or arm 11. Said notch or slot 10 is preferably V-shaped, as shown in Fig. 1, and it is adapted to receive a picture frame hook 75 "H," as shown in Fig. 2, in which said hook is suspended from the arm or tongue 11 in a position to be placed upon a picture frame molding.

The embodiment of the invention, illustrated in Figs. 3 and 4, is composed of a single piece of wire which is bent adjacent to its center into U-form to provide the head 2* and the spaced parallel arms 3*, 4*, which latter have their ends bent upwardly to form hooks 9*. Each of the arms 3*, 4* is formed by doubling the wire upon itself and the outer member of the arm 3* is bent inwardly at right angles to provide an arm or tongue 11* which is spaced from the cross portion 90 of the U-shaped head 2* to provide the slot or opening 10*. Said arm 11* is adapted to support a picture frame hook "H," as shown in Fig. 3, and in the same manner in which the arm or tongue 11 supports the hook "H," 95 as seen in Fig. 2. The inner member of the arm 4* is bent inwardly at right angles to provide a centrally-disposed horizontal portion 5* and then downwardly at right angles to provide a vertical portion 6*. The portions 5* and 6* form an attaching shank for the head and are adapted to engage the upper end and one side of the pole 1* to which they are secured by staples or similar fastenings 6*.

100 The device is primarily designed for hanging up and taking down picture frames without the use of a step ladder or the like, but it may be used for other purposes, as presently explained. When it is desired to 110 hang a picture frame, the hook "H" is supported upon the tongue or arm 11, as in

Fig. 2, or upon the tongue or arm 11^a, as in Fig. 3, and the head of the device is then elevated above the molding and lowered so that the hook "H" will drop upon the latter, the tongue or arm being then slipped laterally or sidewise out of the hook. The head is then lowered and the wire upon the picture frame is stretched across the hooks 9 or 9^a and the head is again elevated so that the portion of the wire between said hooks may be lowered into the hook "H" as will be readily understood. By reversing this operation, the frame may be readily removed from the hook "H," or from a nail on which it is suspended.

It will be noted that by disposing the head in an inclined position and providing the arms 8 at the lower portion of the head and a single upturned hook or projection 9 at the lower end of each of the arms, the device may be quickly and easily engaged with or disengaged from a picture frame wire. This feature is exceedingly advantageous since the device will adjust itself upon the wire and the latter need not be placed by hand in engagement with the hooks 9. The provision of the laterally projecting tongue or arm 11 at the upper end of the head permits the molding hook H to be suspended from the device so that there will be no danger of it being shaken off of the head while being raised or lowered and so that it may be easily lowered upon a molding and released by the head.

The device may be used for holding a dustcloth or the like which may be readily wrapped around the head and its end held by wedging it into the tapered slot 11 or between the resilient tongue 11^a and the upper cross bar of the U-shaped head 2^a, as will be readily understood. The provision of the slot or opening 10, 10^a enables the keys of gas burners, electric lights and the like to be readily turned, since said keys or finger pieces may be easily inserted in said slots or openings.

The device may be further used for picking up and lifting various articles in store windows, upon store shelves, etc.

Having thus described my invention what I claim is:

1. A device of the character described comprising a handle and a head at one end thereof provided with a laterally projecting horizontally disposed arm spaced from the

head and connected to it at one end, whereby a picture frame molding hook may be suspended from said arm, substantially as set forth.

2. A device of the character described comprising a handle and a head at one end thereof arranged in a downwardly inclined position and having at its lower portion downwardly inclined spaced arms with their lower extremities turned upwardly to provide hooks, whereby the device may be readily engaged with and will be self adjusting upon a picture frame wire.

3. A device of the character described comprising a handle having a beveled upper end, a head in the form of a sheet metal plate secured upon the beveled upper end of the handle in a downwardly inclined position, the lower portion of the head being slit to provide spaced arms and an intermediate inwardly bent portion to serve as an attaching shank for engagement with a handle, said arms being inclined downwardly and having their lower ends bent upwardly to provide hooks, substantially as and for the purpose set forth.

4. A device of the character described comprising a pole or handle provided with a beveled upper end, a lifting and supporting head attached to said end of the pole and constructed of sheet metal, said head being of substantially rectangular form and having one end slit to provide spaced arms and an intermediate portion, the latter being bent angularly and curved to provide a shank to engage the pole, the body portion of the head being adapted to rest upon the beveled end of the pole and being apertured, and the lower ends of said arms being bent to provide hooks, the upper end of the body of the head being formed upon one side with a transverse notch or slot to provide a transverse tongue or arm, a fastening passed through the aperture in the head and into the end of the pole, and transverse fastenings passed through the shank and into the pole, substantially as and for the purposes set forth.

In testimony whereof I hereunto affix my signature in the presence of two witnesses. 105

EVERETT W. WOLLAM.
